[57] CLAIM

I claim the ornamental design for a cap protector and display device, as shown and described.

DESCRIPTION

FIG. 1 is a perspective view of a cap protector and display device, showing my new design in an open position;

FIG. 2 is a right side elevational view of the cap protector and display device in an open position, wherein the right side view is a mirror image thereof;

FIG. 3 is a front view of the cap protector and display device of my design in an open position;

FIG. 4 is a rear view of the cap protector and display device in an open position;

FIG. 5 is a top view thereof;

FIG. 6 is a bottom view of the cap protector and display device in an open position; and,

FIG. 7 is a perspective view of the cap protector and display device in a closed position with the device oriented in a vertical display position.
